PANEL FOR AN AUTOMATIC TELEPHONE ANSWERING DEVICE

Neal J. Buglewicz, Hermosa Beach, Calif. (12 Empty Saddle Road, Rolling Hills Estate, Calif. 90274)

Filed Mar. 26, 1971, Ser. No. 128,652

Term of patent 14 years

Int. Cl. D14—03

U.S. Cl. D26—14 A

FIG. 1

FIG. 2

FIG. 3

FIG. 1 is a plan view of a panel for an automatic telephone answering device showing my new design;

FIG. 2 is a side elevational view; and

FIG. 3 is an end elevational view thereof.

I claim:

The ornamental design for a panel for an automatic telephone answering device, substantially as shown.
